Primary Examiner — Jack Reickel*Assistant Examiner* — Russell Carnell Smith, Jr.(74) *Attorney, Agent, or Firm* — Maschoff Brennan(57) **CLAIM**

The ornamental design for a kiosk as shown and described.

DESCRIPTION

FIG. 1 is a front view of a kiosk, showing our new design; FIG. 2 is a top view thereof;

FIG. 3 is a back view thereof;

FIG. 4 is a bottom view thereof; and,

FIG. 5 is a front perspective view thereof.

The broken line showing of a kiosk is included for the purpose of illustrating portions of the article and forms no part of the claimed design.

1 Claim, 5 Drawing Sheets(56)
